DESIGN FOR A PROPELLED VEHICLE

Hugh L. Forman, New York, N. Y.

Application January 5, 1938, Serial No. 74,099

Term of patent 3½ years

To all whom it may concern:

Be it known that I, Hugh L. Forman, a citizen of the United States of America, residing at Borough of Manhattan, city, county, and State of New York, have invented a new, original, and ornamental Design for a Propelled Vehicle, of which the following is a specification, reference being had to the accompanying drawings, forming part thereof.

In the drawings:—

Fig. 1 is a front perspective view.

Fig. 2 is a side elevation of a propelled vehicle, showing my new design, and

Fig. 3 is a rear perspective view of the vehicle.

I claim:—

The ornamental design for a propelled vehicle, as shown.

HUGH L. FORMAN.
